UNITED STATES PATENT OFFICE.

PHILIPPE DE CLAMECY, OF CHARLESTOWN, MASSACHUSETTS, ASSIGNOR TO CORONA TYPEWRITER COMPANY, INC., OF GROTON, NEW YORK, A CORPORATION OF NEW YORK.

TYPEWRITING MACHINE.

Application filed October 3, 1918. Serial No. 256,671.

To all whom it may concern:

Be it known that I, PHILIPPE DE CLAMECY, a citizen of the United States, and a resident of Charlestown, in the county of Suffolk and State of Massachusetts, have invented certain new and useful Improvements in Typewriting Machines, of which the following is a specification.

The object of this invention is to provide a simple and practical device for automatically rewinding the ribbon on the empty reel; and the invention consists of certain novel features of construction hereinafter described and claimed.

15 In the drawings—

Fig. 1 is a view partly in vertical section and partly in side elevation showing my automatic device applied to one of the spools:

20 Fig. 2 is a plan view of Fig. 1;

Fig. 3 designates views of the snap-spring for fastening the end of the ribbon to the reel-hub;

25 Fig. 4 is a plan view of the tripping device detached from the reel;

Fig. 5 is a side elevation of the same;

Fig. 6 is a view similar to Fig. 5, but showing the trip-arms at a different working angle, the object of which is to reduce the strain on the ribbon;

30 Fig. 7 is a horizontal section on the line 7—7 of Fig. 1;

Fig. 8 is a vertical section on the line 8—8 of Fig. 7;

35 Figs. 9, 10 and 11 are different views of the spool or reel.

Referring to the drawings by reference-characters, the numeral 3 designates a pair of fingers whose lower ends extend through slots 31 in the lower flange of the ribbon spool or reel and are pivoted at 38 to dependents ears 29' carried by said lower flange, the positions of these pivots 38 being such that when the fingers stand upright they lie in vertical grooves 3' formed in opposite sides of the reel hub 25. The upper edges of these fingers extend up through radial slots 27 formed in the upper flange of the reel. When the ribbon 27' is wound upon the hub, the fingers 3 are confined in the channels 3'. The end of the ribbon may be fastened to the hub in any suitable manner; I prefer employing a snap-spring or clamp 23 such as shown in Fig. 3.

Each of the fingers 3 is provided at its 55 lower end with a radial arm 7 extending outwardly, and a link 8 is pivoted at 39 to the outer end of each of these arms. These links depend downwardly and inwardly and are pivotally attached at 40 60 to the upper end of a cone 9 whose small end faces downwardly and which is provided with an axial bore to enable it to slide readily on the reel-shaft. Between the top of this cone and the thrust washer 65 42 is a light coil-spring 41, said washer being arranged to thrust against shoulders on the lower ends of fingers 3, so that the normal tendency of spring 41 is to spread the fingers 3 radially apart and force the 70 cone 9 downwardly. The ribbon windings on the reel hold the fingers 3 in the hub-channels and the cone 9 in its upper position, with the spring 41 under compression.

Slidably mounted on a part 16 of the 75 frame of the machine is a bar 15 which extends across the machine and is provided at each end with a pull-ring 34 through which the adjacent reel-shaft extends and which lies in the path of the adjacent slideable cone 9. This bar is guided by suitable guides 10 and 14 affixed to the frame-member 16, and at each end this bar is provided with a depending lug 20 on which is supported a bar 19, the bar being supported 80 in slots 37 to permit it to have a sidewise movement fore and aft of the machine. At each end of this bar 19 is provided a pawl 21 which is adapted to engage a ratchet-wheel 22 affixed to the adjacent reel-shaft. 85

In Fig. 1, the pawl 21 at the left is out of engagement with its associated ratchet-wheel and the pull-ring 34 is in position to be actuated to pull bar 15 toward the left when the cone is thrown downwardly by 90 its spring 41. At the opposite side of the machine, it will be understood, the corresponding parts are in the reverse position, namely, the pawl in engagement with the ratchet and the center of the pull-ring shifted laterally to the right of the axis of the elevated cone. With the parts in these positions, it will be seen that the vibration of the bar 19 backward and forward causes the rotation of the right hand reel-shaft 100 which has its ratchet-operating mechanism in operative position. This bar 19 may be reciprocated in any suitable manner; that

is to say, it may be itself a universal bar arranged in position to be struck by the type-bars or it may be connected to the usual universal bar of the machine and be reciprocated in unison therewith.

Upon exhaustion of the ribbon from the spool which is unwinding, the fingers 3 are released and the spring 41 throws down the shifter-cone. The cone impinges against the inner side of the outer portion of the laterally offset pull-ring and thus reverses the spool-driving mechanism by pulling the rod 15 endwise far enough to bring the idle pawl 21 into position where it will operate upon the spool of the exhausted reel. This operation will of course shift the pull-ring at the other end of the rod 15 into position for actuation by the shifter-cone at that side when the reel at that side in turn becomes exhausted. After each actuation, cone 9 is drawn upwardly away from the pull-ring by the pressure of the rewinding ribbon upon the fingers 3, as is evident, so that the shifter-cones are held up out of the way of the pull-rings except during the short period of time it takes to make one or two turns in the rewind. The idea of using the cone for actuating the reverse-rod 15 is that, irrespective of the position of the reel, the cone will always be in position to actuate the pull-ring when the cone is thrust downwardly.

Any suitable devices may be employed to hold the reversing-bar 15 in either of its two positions; I have shown a round-ended pin 12 which is confined in a recess 17 formed in the frame-part 16 and is actuated by a coil-spring 18 to normally press against the under side of the bar 15, this bar being provided with a notch 13 to receive this pin when the adjacent ratchet-device is in engagement. A similar holding device is arranged at the other side of the machine. Instead of two of these holding devices, one at each side of the machine, a single one may be employed, this single one being adapted to cooperate with two adjacent notches 13.

It will be observed that the slots 37 curve upwardly, it being desirable to curve these slots on the arc of a circle described from the center of the rocking point of the universal bar of the machine, to thereby avoid binding of the rod 19 in said slots 37. To prevent torsion of the fingers 3, they are arranged to extend up through the slots 27 and have their side edges fit against the side walls of the slots when the pull of the rewinding ribbon forces the fingers 3 back into the hub-slots 3'; this ensures ease of movement of the parts by preventing binding, and this ease of movement together with the shape and proportions of the levers formed by the fingers 3 and their connected arms 7 reduces the strain on the ribbon in raising the cone to a minimum; for instance, the

parts may be so proportioned that if the pull of the ribbon on arms or fingers 3 is 1 ounce, the upward pull at 39 may be, say, 4 ounces, thus ensuring compression of the spring 41 with the least possible strain on the ribbon. 70

The nature and scope of the invention having been thus indicated and its preferred embodiment having been specifically described, what is claimed as new is:

1. In a typewriting machine, a ribbon-reel, 75 a cone rotating therewith and means which upon the exhaustion of the ribbon reciprocates the cone, and a ribbon-drive adapted to be reversed by the reciprocation of the cone.

2. In a typewriting machine, a ribbon-reel, 80 a cone carried thereby and rotated therewith, means carried by the reel for reciprocating the cone upon exhaustion of the ribbon, and means operated by the reciprocation of the cone for reversing the ribbon-drive. 85

3. In a typewriting machine, a ribbon-reel, 90 a shifter carried by the reel and means also carried by the reel for automatically reciprocating this shifter on exhaustion of the ribbon, and a ribbon-drive adapted to be reversed by reciprocation of said shifter.

4. In a typewriting machine, a ribbon-reel, 95 a finger pivoted therein and adapted to be held up by the ribbon winding, a shifter and means connecting it to said finger to reciprocate the shifter when the finger is released, a spring for actuating the finger and the shifter, and a ribbon-drive adapted to be reversed by the movement of the shifter.

5. Ribbon feeding mechanism for writing 100 machines, comprising a pair of ribbon spools, driven members rotatable with the spools, driving means, a drive-reversing device slidably endwise for connecting the driven members alternately with the driving means, and a pair of ribbon-controlled spring-operated cam devices associated with different spools and shiftable alternately by their operating springs transversely of said reversing device upon exhaustion of the ribbon from the respective spools and slidably engaging said reversing device to cam the same endwise in opposite directions, each cam device shifting the reversing device during movement of the cam device by its operating spring. 110 105 115

6. Ribbon feeding mechanism for writing 120 machines, comprising a pair of spool shafts, spools rotatable with the shafts, driven members rotatable with the shafts, driving means, a feed-reversing member shiftable endwise in opposite directions transversely of the shafts for connecting the driven members alternately with the driving means, a pair of ribbon-controlled cam devices recipro- 125 cable longitudinally on the shafts upon exhaustion of a ribbon from the respective spools to alternately slidably engage and shift the feed-reversing member endwise in opposite directions, each cam device actuating the reversing member during move- 130

ment of the cam device in one direction on the shaft.

7. In a typewriting machine, a ribbon-reel, a pair of pivoted fingers adapted to lie against the hub and each provided with a radial arm, a cone slidable on the reel-shaft connected to said arms by pivoted links, a spring confined between the cone and the lower ends of said fingers, and a ribbon-drive adapted to be reversed by the reciprocation of said cone.

8. In a typewriting machine, a ribbon-reel and an automatic shifter carried thereby, a ribbon-drive embodying a slidable bar carrying a pull-ring adapted to be engaged by said shifter, and a bodily-movable rod carried by said bar and provided with a pawl adapted to engage the ratchet-wheel of the spool-shaft.

9. In a typewriting machine, a ribbon-drive embodying reels whose upper flanges are radially slotted, levers having arms extending upwardly from the under side of each reel into said slots, each of these levers being pivoted to the lower flange of the reel and provided with outwardly-extending arms, and spring-actuated shifting devices connected to said outwardly-extending arms.

10. In a typewriting machine, the combination of a pair of ribbon spools, a pair of feed-reversing cones, ribbon-controlled means for reciprocating the cones, and means for rotating the spools settable by said cones successively upon exhaustion of the ribbon from a spool to reverse the direction of feed of the ribbon.

11. In a typewriting machine, the combination of a pair of ribbon spools, a pair of feed-reversing cones, ribbon-controlled means for reciprocating the cones, a pair of driven members rotatable with the spools, a pair of driving members, and means shiftable alternately in opposite directions by the cones for rendering first one and then the other of said driving members effective to actuate its associated driven member.

12. In a typewriting machine, a ribbon drive embodying a reciprocable bar having a ring at each end and carrying the feed-pawls, and a device associated with each spool for engaging in one of said rings for shifting said bar upon exhaustion of the ribbon.

13. Ribbon feeding and reversing means comprising a pair of ribbon spools, a pair of bell-crank levers rotatable with each spool having arms adapted to be pulled toward each other by a ribbon wound upon the

spools and arms extending radially of the spools, means for rotatably supporting the spools, a pair of cones, a pair of links connecting each cone with the radially extending arms of one pair of bell-crank levers, springs for moving the cones upon exhaustion of a ribbon from the spools, and means operable by the cones alternately for rendering a spool-rotating means effective on one spool and ineffective on the other spool.

14. Ribbon feeding and reversing mechanism comprising a pair of rotatable shafts, spools held to the shafts to rotate therewith, ratchet wheels fixed on the shafts, a vibratory pawl carrier, pawls on said carrier, a reversing member shiftable transversely of the shafts and connected with the pawl carrier for moving the carrier transversely of its path of vibration to render one pawl effective and the other ineffective, and ribbon-retracted spring-operated cam devices for shifting said member alternately in opposite directions, each cam device being movable transversely of the reversing member and arranged to shift said member during movement of the device by its operating spring.

15. Ribbon feeding and reversing mechanism comprising a pair of rotatable shafts, spools held to the shafts to rotate therewith, ratchet wheels fixed on the shafts, a vibratory pawl carrier, pawls on said carrier, a member shiftable transversely of the shafts and connected with the pawl carrier for moving the carrier transversely of its path of vibration to render one pawl effective and the other ineffective, spring-pressed devices slidably held to the shafts for shifting said member alternately in opposite directions, and ribbon-actuated means for retracting said devices.

16. In a ribbon feeding mechanism, the combination of a pair of ribbon-spools, driving means, driven members rotatable with the spools, a feed-reversing member having a pair of circular apertures therein and connected with the driving means, a pair of cones rotatable with said spools and reciprocable in said apertures to shift said reversing member alternately in opposite directions to connect the driven members alternately with the driving means, and ribbon-controlled means for reciprocating the cones alternately upon exhaustion of a ribbon from the respective spools.

This specification signed this fifth day of September, A. D. 1918.

PHILIPPE DE CLAMECY.
